R. P. WRIGHT,
COMBINED STRIPPER AND PRESSURE RELEASE,
APPLICATION FILED DEC. 2, 1916.

1,224,055.

Patented Apr. 24, 1917.

UNITED STATES PATENT OFFICE.

REA P. WRIGHT, OF WASHINGTON, DISTRICT OF COLUMBIA, ASSIGNOR TO JOHN FRANCIS HEMENWAY, OF NEW YORK, N. Y.

COMBINED STRIPPER AND PRESSURE-RELEASE.

1,224,055.

Specification of Letters Patent. Patented Apr. 24, 1917.

Application filed December 2, 1916. Serial No. 134,640.

To all whom it may concern:

Be it known that I, REA P. WRIGHT, a citizen of the United States, residing at Washington, in the District of Columbia, have invented certain new and useful Improvements in Combined Stripper and Pressure-Releases, of which the following is a specification, reference being had thereto in the accompanying drawing.

10 This invention relates to certain new and useful improvements in clothes wringers and is a companion case of my application executed even date herewith, the object being to provide a pivotally mounted stripper

15 having means for holding the movably mounted pressure screw carrying members in predetermined position in such a manner that when the stripper is rocked on its pivots by the upward movement of one of

20 the pressure rolls, the pressure screw carrying member will be released in order to allow the pressure rolls to move vertically.

Another object of my invention is to provide a device which is exceedingly simple and cheap in construction and one which can be readily attached to the ordinary construction of wringer now in use.

Another object of my invention is to provide novel means for adjusting the same in respect to the pressure roll.

Other and further objects and advantages of the invention will be hereinafter set forth and the novel features thereof defined by the appended claims.

35 In the drawings,

Figure 1 is a side elevation, partly in section, of a clothes wringer showing the application of my improved construction of pressure release and stripper thereto.

40 Fig. 2 is a vertical section taken on line 2-2 of Fig. 1.

Fig. 3 is a perspective view of the stripper and release detached, and

45 Fig. 4 is a detail perspective view of a slightly modified form of a stripper showing the same in the form of a trough for conveying any water thrown from the roller to one side of the wringer.

Like numerals of reference refer to like parts in the several figures of the drawing. 50

In carrying out my invention I employ a frame 1 having the usual slotted side bars 2, in which are mounted superposed pressure roll carrying shafts 3 and 4 arranged in bearings and provided with rubber pressure rolls 5 and 6. The upper bearings for the pressure roll carrying shaft 4 are provided with spring supports 7, on which are mounted coiled pressure springs 8 engaged by bearing plates 9 carried by pressure bar 9', as shown in Fig. 1.

Movably mounted within the slotted side bars 2 of the wringer frame is a top bar 10 having threaded boxes 11 at its ends, carrying pressure screws 12 adapted to engage the bearing plates 9 of the pressure bar 9' for exerting the proper pressure on the pressure springs. The above construction of wringer is similar to that class of wringer now in general use, with the exception that the mov- 70 ably mounted top bar is employed.

In applying my improved construction of stripper and release to a wringer herein shown and described, I secure to the inner face of each of the side bars 2 of the frame 75 1, a plate 13 which is provided with slots 14 through which screws 15 extend for securing the plate to the side bars in such a manner that they can be adjusted vertically in respect to the pressure rolls of the 80 wringer. The plates are provided with apertured bosses 16 forming bearings for trunnions 17 formed on the end of a stripper board 18 which is provided with a beveled lower edge 19 adapted to be held adjacent the 85 upper pressure roll 6, as shown in Fig. 2.

Secured centrally to the stripper board 18 is a retaining member 20 which is provided with a slot 21 through which extends a bolt 22 carrying a thumb nut 23 for adjusting 90 the retaining member 20 on the stripper board 18. The retaining member 20 is provided with an offset portion 24 terminating at its upper end in a hook 25 adapted to extend into an eye 26 carried by the movably 95 mounted top bar 10 for retaining the top

bar in predetermined position within the wringer frame. In this construction when the upper pressure roll 6 is moved vertically by a foreign object being drawn between 5 the pressure rolls of the wringer, the stripper board 18 is rocked on its pivots so as to move the hook 25 out of the eye 26 of the top bar 10, which releases the top bar and allows the same to move vertically within 10 the slotted side bars in order to release the pressure on the pressure rolls. In the normal position of the device as shown in Figs. 1 and 2, the beveled lower edge 19 of the stripper board is held adjacent the upper 15 pressure roll 6 so as to prevent the clothes from winding around the roll.

In the modification shown in Fig. 4, I provide a stripper board 27 in the form of a trough at its lower edge in order to provide 20 a gutter for carrying any water thrown from the roller to one side of the machine, the stripper being provided with the usual trunnions for pivotally mounting the same on the frame of the wringer, as by providing 25 the gutter with an inclined bottom, the liquid thrown from the pressure roll will be conveyed to one side of the wringer. In this form, it is of course understood, that a retaining member is carried by the stripper 30 per for holding the pressure screw carrying member in position within the wringer frame.

I claim:

1. A clothes wringer comprising a frame 35 having pressure rolls and pressure means for said rolls mounted therein, a top bar movably mounted in said frame, a stripper member pivotally mounted in said frame above the upper pressure roll, and a retaining 40 member carried by said stripper member for holding said top bar in predetermined position within said frame, said retaining member being moved out of engagement with said top bar on the separation of said 45 rolls for releasing said pressure means.

2. A clothes wringer comprising a frame having pressure rolls and pressure means for said rolls mounted therein, a top bar movably mounted in said frame having 50 means for adjusting said pressure means, a stripper member pivotally mounted in said frame above the upper pressure roll, an eye carried by said top bar, and a retaining member adjustably mounted upon said stripper 55 member having a hook engaging said eye.

3. A clothes wringer comprising a frame having pressure rolls and pressure means for said rolls mounted therein, a top bar movably mounted in said frame having pressure 60 means for adjusting said pressure means, a pivotally mounted stripper member adjustably mounted in said frame above the upper pressure roll, and a retaining member adjustably mounted on said stripper member coact-

ing with said top bar for normally holding 65 said top bar in predetermined position within said frame.

4. A clothes wringer comprising a frame having pressure rolls and pressure means for 70 said rolls mounted therein, a top bar movably mounted in said frame having pressure screws for adjusting said pressure means, bearings adjustably mounted on said frame, a stripper member having trunnions pivotally mounted in said bearings, said stripper member arranged adjacent the upper pressure roll, an eye carried by said top bar, and a retaining member carried by said stripper member, having a hook extending into said eye for normally holding said top bar in predetermined position within said frame. 75

5. A clothes wringer comprising a frame having pressure rolls and pressure means for 80 said rolls mounted therein, a top bar movably mounted in said frame having pressure screws for adjusting said pressure means, an eye carried by said top bar, a pivotally mounted stripper member mounted in 85 said frame above the upper pressure roll, and a retaining member adjustably carried 90 by said stripper member having a hook portion extending into said eye for holding said top bar in predetermined position within 95 said frame.

6. A clothes wringer comprising a frame 100 having pressure rolls and pressure means for said rolls mounted therein, a top bar movably mounted in said frame having pressure screws for adjusting said pressure means, a stripper member pivotally mounted in said frame, a retaining member carried by said stripper member for holding said top bar in predetermined position within said frame, said retaining member being moved out of engagement with said top bar on the separation of said rolls for releasing said pressure means. 105

7. A clothes wringer comprising a frame having pressure rolls and pressure means for said rolls mounted therein, a top bar movably mounted in said frame having pressure screws for adjusting said pressure means, plates adjustably mounted on the side bars of said frame having bearings, a stripper member having trunnions pivotally mounted in said bearings, said stripper member having its lower edge arranged adjacent the upper pressure roll, an eye carried by the top bar, and a retaining member adjustably mounted on said stripper member having a hook extending into said eye for holding said top bar in predetermined position within said frame, said hook being moved out of engagement with said eye on the separation of said pressure rolls. 110 115 120

8. A clothes wringer comprising a frame having pressure rolls and pressure means for said rolls mounted therein, a movably mount-

ed pressure screw carrying member mounted in said frame, a pressure screw carried by said member for adjusting said pressure means, a stripper member pivotally mounted in 5 said frame above one of said pressure rolls, and a retaining member carried by said stripper member for normally holding said movably mounted pressure screw carrying

member in predetermined position within said frame. ¹⁰

In testimony whereof I hereunto affix my signature in the presence of a witness.

REA P. WRIGHT.

Witness:

N. CURTIS LAMMOND.
